UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

STOCKING AND METHOD OF MAKING THE SAME.

1,327,217.

Specification of Letters Patent.

Patented Jan. 6, 1920.

Application filed July 7, 1916. Serial No. 103,069.

To all whom it may concern:

Be it known that I, ROBERT W. Scott, a citizen of the United States, and resident of Boston, in the county of Suffolk and State of Massachusetts, have invented new and useful Improvements in Stockings and Methods of Making the Same, of which the following is a specification.

This invention relates to the manufacture of stockings. I shall describe as one instance thereof a stocking and the method of making said stocking as a seamless tubular article having ordinary seamless toe and heel pockets, and having the leg portion knit with double the number of wales contained in the foot portion, the whole fabric being composed of non-rib stitches; that is to say, all of the stitches being drawn to the same face of the fabric. My invention relates to an improved procedure for making such an article, so as to form on a series of needles an improved structure at the toe portion of the stocking in aid of the operation of looping the toe seam, a leg of multiple course fabric of the accordion type and an inturned welt at the top of the same fabric as the leg.

I have explained in my copending application Serial No. 94,232, [Letters Patent No. 1,194,675, dated August 15, 1916] the manufacture of such a stocking, my present invention relating to improvements upon the method and article of my said application, whereby I have provided looper's rounds preceding the position of the toe seam characterized by a selvage adapted to be easily raveled, and provided the article with an end-finish constituting an inturned welt of an improved structure, as well as provided an article and method adapted for advantageous making and practice by machines.

In the accompanying drawings,

Figure 1 is a side elevation, partly broken away, of the article completed except for the closure of the toe seam;

Fig. 2 is an enlarged diagram section longitudinally of the stocking through the welt;

Figs. 3, 4 and 5 are comparative diagrams showing needles and the inner or back side of the fabric at the needles respectively at the beginning of the stocking, at the foot portion and at the end of the operation;

Fig. 6 is a diagram plan of a circle of needles illustrating one instance of an in-

strument upon which the manufacture can be carried out;

Fig. 7 is a view similar to Fig. 6 showing the needles active and inactive at the toe, foot, and heel;

Fig. 8 is a similar view illustrating the production of double-course accordion fabric;

Fig. 9 is a similar view illustrating the operation of taking bights for the welt; and

Fig. 10 is a diagram illustrating the formation of the welt.

Referring now to Fig. 1, knitting is begun at the selvage S formed on the bare instruments such as a closed row or series of needles, illustrated as a circle of needles *n* in Figs. 6 to 9. The initial yarn 1, Fig. 3, may be taken by or supplied to recurrent needles *n'*, the yarn passing behind intervening needles *n* until all of the needles *n'* are so supplied, and a second course 2 is then supplied to all of the needles, and the first course cast off, thereby forming a selvage; and one or more courses 3 may then be knit upon all of the needles (Figs. 3 and 6). The selvage structure is thus formed upon all of the needles. It is desirable that the selvage shall be formed so as to be readily raveled from the following waste-fabric or looper's rounds *f*, which for ease of looping and economy of wasted yarn should be of a number of needles wales less than the number of needles in the machine. The fabric *f* is in aid of looping the toe seam by sewing together the places indicated by the dotted lines *s'*. Such sewing takes place upon a looping machine upon which the fabric is impaled by points entering the lines *s'*, the selvage S and the fabric *f* being raveled away. I prefer to form the selvage and one or more courses 3 on all the needles as above described, and then to cast off the loops in course 3 or a subsequent course from the needles *n*. By this operation, if the instrument of manufacture is a machine, the selvage will not only have enabled the fabric *f* to be started upon the bare needles, but the structure comprising the courses 1, 2, 3, in which the course 3 has cast-off loops *a* formed at and cast off from the needles *n*, whatever the instrument of manufacture, will then constitute an edge easily raveled, for instance by pulling on the yarn 1 or the yarn 2, whereby to release the loops *a* from

the loops of the yarn 2 engaged by them, thus freeing the yarn 1 from any engagement and leaving the yarn 2 free to be pulled endwise through the loosened sinker wales 5 lying between the needle wales from the needles n' . The remainder of the fabric f will also ravel freely, as will be apparent to skilled knitters.

The toe, foot, and heel are knit upon the 10 needles n' only, preferably as indicated in Fig. 7, the needles n^2 , from which the loops were cast off subsequent to the selvage remaining idle and out of action. At this 15 stage the knitting is preferably single-course knitting, as will result from forming a knitting wave in the needles at and taking yarn from a single main yarn feed y . (See Fig. 7). The heel pocket h and toe pocket t may be knit upon a segment of the needles n' only, 20 as usual, by reciprocal operations with the yarn or any substituted or additional yarn fed from the yarn feed y to the needles n' only.

Having completed the foot F and the heel 25 h and a few courses c above the heel by the usual operations on needles n' only, the character of the fabric is changed by restoring the inactive needles n^2 to action, so that all the needles will take thread and knit 30 at the main yarn feed y , while at a supplemental yarn feed x the needles are so manipulated that the needles n' only take the yarn and knit, the intervening needles passing below the yarn receiving level, the arrangement 35 of yarn feeds and active and inactive needles being that indicated in Fig. 8. This arrangement results in the production of a fabric commonly known as accordion fabric, an instance of which is shown in Fig. 10. 40 This fabric is produced to a sufficient extent to form the leg L of the stocking.

I have referred in my said application Serial No. 94,232, to alternative procedures for forming a welt after knitting such a leg, 45 and I will now describe a preferred species of operation producing an improved structure in which the fabric of an in-turned welt W consists of accordion fabric like the leg L .

50 Referring now to Figs. 9 and 10, having completed the leg L to the course z , preferably a course of the main yarn fed from main yarn feed y , I form in the course z bights w preferably by rendering the needles n^2 inactive in a low position while withholding their previous loops of the yarn from main yarn feed y . The bights w may be taken by transfer implements T , for instance according to the method disclosed in my co-pending application Serial No. 49,161, [Letters Patent No. 1,189,744, dated July 4, 1916,] filed September 7, 1915. This operation may take place upon a machine knitting both at the yarn feed y and the yarn 55 feed x the respective yarns forming the ac-

cordion fabric. Having taken the bights w the implements T are manipulated to retain said bights during the continued production of accordion fabric in sufficient quantity to form an in-turned fold W as illustrated. 70

The bights w taken on the instruments T are now returned to the needles n^2 from which they were removed, thereby fastening down the welt w upon the knitting of subsequent fabric. In order to prevent free 75 raveling of the subsequent fabric and release of the welt, I prefer at this point to cease operations at the yarn feed x in order to form plain fabric from yarn supplied at main feed y only for a few curling 80 courses following the interknitting of the united course z with the subsequently formed welt fabric, as illustrated in Figs. 1, 2, 5 and 6. The accordion fabric does not display any marked tendency to curl toward the face side thereof, but plain fabric as illustrated at C in Fig. 5, when freed from the needles, curls toward its face side or in the direction away from the observer in Fig. 5. Fig. 5 shows the juncture of the welt W 90 with the leg L , viewed from the back or inside of the fabric. When a sufficient extent of the fabric C has been formed the fabric is cast off all of the needles as illustrated in Fig. 5, and upon being so released 95 will curl with its last-knit edge within the fold so formed, as illustrated in Figs. 1 and 2.

One advantage of a stocking having a welt formed in the described manner of accordion 100 fabric as many wales in width as and capable of stretching laterally to as great a width as the leg lies in thus providing a welt having a retractile quality uniform with that of the leg, such stockings when 105 finished having no tendency to flare outwardly at the welt.

Trade requirements for stockings of the kind most suitable for making of the described fabric are not wholly satisfied by 110 in-turned or out-turned welt structures of plain fabric because of the difficulty found in finishing the plain fabric welt in a state contracted laterally to conform to the width of the finished leg. 115

By the described method of knitting, a satisfactory suture at the course z is formed without changing to a heavier yarn, the yarn fed at the main feed y as the heavier element of the accordion fabric being utilized 120 for the uniting or suture course. By the described method I have also provided for withholding loops, holding needles out of action and casting off during the making of the article upon the same intervening needles 125 n^2 only [except at the end of the operation when casting-off is accomplished at all of the needles by ceasing to feed yarn] and have thereby adapted the article to be produced and the method to be practised upon a ma- 130

chine adapted to knit continuously upon needles *n'* recurrent between the intervening needles whenever knitting at all.

What I claim is:

- 5 1. A stocking comprising a seamless toe, foot and heel of plain fabric, a tubular leg continuous with foot and heel of multiple-course accordion fabric having a greater number of wales than the foot, and having 10 an integral welt of multiple-course accordion fabric at the top thereof.
2. A stocking knit from toe to top comprising a seamless toe, foot and heel of plain fabric, a tubular leg continuous with foot 15 and heel of multiple-course accordion fabric having a greater number of wales than the foot, and having an integral welt of multiple-course accordion fabric having as many wales as the leg at the top thereof.
- 20 3. A stocking knit from toe to top comprising a seamless toe, foot and heel of plain fabric, a tubular leg continuous with foot and heel of multiple-course accordion fabric having a greater number of wales than the 25 foot, and having an integral welt of multiple-course accordion fabric at the top thereof, followed by curling courses of plain fabric.
4. A stocking knit from toe to top comprising 30 a seamless toe, foot and heel of plain fabric, a tubular leg continuous with foot and heel of multiple-course accordion fabric having a greater number of wales than the foot, and having an integral welt of multiple-course accordion fabric at the top thereof, followed by curling courses of plain 35 fabric having as many wales as welt and leg.
5. A stocking having a leg knit of a plurality of yarns as accordion fabric comprising 40 wales of a single component yarn only intervening between wales in which successive courses are of different yarns, and having a welt comprising an extent of similar fabric continuous with the wales of the leg fabric at one end and united to the leg fabric at the other end by bights of the yarn of said single-yarn wales engaged by loops of the welt fabric at said other end.
6. A stocking having a leg knit of a plurality 45 of yarns as accordion fabric comprising wales of a single heavier component yarn only intervening between wales in which successive courses are alternately of lighter and heavier yarns, and having a welt comprising an extent of similar fabric continuous with 55 the wales of the leg fabric at one end and united to the leg fabric at the other end by bights of the heavier yarn engaged by loops in said wales of heavier yarn at the other 60 end.
7. A stocking blank knit from toe to top comprising a raveling selvage having loops in wales terminating in a free loop followed by a seamless toe, foot and heel of plain

fabric, and a tubular leg continuous with 65 foot and heel of multiple-course fabric having a greater number of wales than the foot.

8. A stocking blank knit from toe to top comprising a raveling selvage having loops in wales terminating in a free loop followed 70 by raveling single-course looper's rounds and a seamless toe, foot and heel of plain single-course fabric, and a tubular leg continuous with foot and heel of multiple-course fabric having a greater number of 75 wales than the foot.

9. A stocking blank knit from toe to top comprising a selvage having a certain number of needle wales, a contiguous section of looper's rounds, and a seamless toe, foot and 80 heel of plain fabric, all having a less number of needle wales than the selvage continuous therewith, and a tubular leg continuous with foot and heel of multiple-course fabric having as many wales as the selvage, the 85 wales of the selvage in excess of the looper's rounds terminating in cast-off loops, whereby the selvage is adapted to be raveled.

10. The art of knitting a seamless stocking on a series of needles comprising first 90 forming a selvage on all of the needles, knitting one or more courses of fabric on said needles, casting off the loops at needles intervening between recurrent needles, and thereafter knitting looper's rounds, a toe pocket, a tubular foot, and a heel pocket on said recurrent needles, and thereafter knitting fabric for the remainder of the stocking on all of the needles.

11. The art of knitting a seamless stocking on a series of needles comprising first forming a selvage on all of the needles, knitting one or more courses of fabric on said needles, casting off the loops at needles intervening between recurrent needles, and thereafter 105 knitting on said recurrent needles single-course looper's rounds, a toe pocket, a tubular foot and heel pocket; and thereafter knitting a leg of multiple-course fabric on all of the needles.

12. The art of knitting a seamless stocking on a series of needles comprising first forming a selvage on all of the needles, knitting one or more courses of fabric on said needles, casting off the loops except at recurrent needles, and thereafter knitting on said recurrent needles single-course looper's rounds, a toe pocket, a tubular foot and heel pocket, and thereafter knitting a leg and integral in-turned welt of multiple-course accordion fabric on all of the needles.

13. The art of knitting a seamless stocking on a series of needles comprising forming a leg of multiple-course fabric on the needles, detaining bights from one of the 125 multiple courses of said fabric, knitting a further extent of multiple-course fabric of the same kind as the leg for a welt, trans-

ferring the detained bights to needles, and knitting curling courses following the uniting-course so formed.

14. The art of knitting a seamless stocking on a series of needles comprising forming a toe pocket, a tubular foot and heel pocket on needles intervening between recurrent unused needles, and thereafter knitting a leg of multiple-course fabric on all of the needles, detaining bights from one of the multiple courses of said fabric, knitting a further extent of multiple-course fabric of

the same kind as the leg for a welt, transferring the detained bights to needles, knitting single-course curling courses following the uniting-course so formed, and casting off the completed product. ¹⁵
